[57] ABSTRACT

An improved form of thermal actuator suitable for use in a MEMS device. The actuator includes a first material such as polytetrafluoroethylene having a high coefficient of thermal expansion and a serpentine heater material having a lower coefficient of thermal expansion in thermal contact with the first material and heating the first material on demand. The serpentine heater material is elongated upon heating so as to accommodate the expansion of the first material.

FIG. 1

FIG. 2

FIG. 3

THERMAL ACTUATOR**FIELD OF THE INVENTION**

The present invention relates to a device and, in particular, discloses a thermal actuator.

The present invention further relates to the field of micro-mechanics and micro-electro mechanical systems (MEMS) and provides a thermal actuator device having improved operational qualities.

BACKGROUND OF THE INVENTION

The area of MEMS involves the construction of devices on the micron scale. The devices constructed are utilised in many different field as can be seen from the latest proceedings in this area including the proceedings of the IEEE international workshops on micro-electro mechanical systems (of which it is assumed the reader is familiar).

One fundamental requirement of modern micro-mechanical systems is need to provide an actuator to induce movements in various micro-mechanical structures including the actuators themselves. These actuators as described in the aforementioned proceedings are normally divided into a number of types including thermal, electrical, magnetic etc.

Ideally, any actuator utilized in a MEMS process maximises the degree or strength of movement with respect to the power utilised in accordance with various other trade offs.

Hence, for a thermal type actuator, it is desirable to maximise the degree of movement of the actuator or the degree of force supplied by the actuator upon activation.

SUMMARY OF THE INVENTION

It is an object of the present invention to provide for an improved form of thermal actuator suitable for use in a MEMS device.

In accordance with a first aspect of the present invention, there is provided a micromechanical thermal actuator comprising a first material having a high coefficient of thermal expansion and a serpentine heater material having a lower coefficient of thermal expansion in thermal contact with the first material and adapted to heat the first material on demand, wherein the serpentine heater material being elongated upon heating so as to accommodate the expansion of first material.

In accordance with a second aspect of the present invention, there is provided a micro-mechanical thermal actuator comprising a first layer having a first coefficient of thermal expansion, a second layer having a relatively higher coefficient of thermal expansion than the first layer, and a heater element in thermal contact with the first and second layers such that, on heating the heater, the actuator moves from a first quiescent position to a second actuation position. Further, the heater element comprises a serpentine layer of poly-silicon, which is sandwiched between the first and second layers. Preferably, the first layer comprises polytetrafluoroethylene, and the second layer comprises silicon dioxide or silicon nitride.

BRIEF DESCRIPTION OF THE DRAWINGS

Notwithstanding any other forms which may fall within the scope of the present invention, preferred forms of the invention will now be described, by way of example only, with reference to the accompanying drawings which:

FIG. 1 is a perspective cross-sectional view of two thermal actuators constructed in accordance with the preferred embodiment.

FIG. 2 is a cross-sectional view of a thermal actuator constructed in accordance with the another embodiment.

FIG. 3 is an exploded perspective view illustrating the construction of a single thermal actuator in accordance with an embodiment of the present invention.

DESCRIPTION OF PREFERRED AND OTHER EMBODIMENTS

10 In the preferred embodiment, a thermal actuator is created utilising a first substance having a high coefficient of thermal expansion and a second substance having a substantially lower coefficient of thermal expansion.

15 Turning now to FIG. 1, there is shown one form of thermal actuator constructed in accordance with the preferred embodiment. The arrangement 1 includes an actuator arm 2 which includes a bottom field oxide layer 3 which has been etched away underneath by means of an isotropic etch of a sacrificial material underneath the field oxide layer 3 so as to form cavity 4.

20 On top of the field oxide under layer 3 is constructed a poly-silicon layer 5 which is in the form of a serpentine coil and is connected to two input leads 7, 8.

25 The poly-silicon coil 5 acts as a resistive element when energised by the input leads which further results in a heating of the poly-silicon layer 5, a corresponding heating of the field oxide 3, in addition to the heating of a polytetrafluoroethylene (PTFE) layer 10 which is deposited on the top of the poly-silicon layer 5 and field oxide 3. The PTFE layer 10 has a high coefficient of thermal expansion (770×10^{-6}) Hence, upon heating of poly-silicon layer 5, the PTFE layer 10 will undergo rapid thermal expansion relative to the field oxide layer 3. The rapid thermal expansion of the PTFE layer 10 results in the two layers 10, 3 acting as a thermal actuator, resulting in a bending of the actuator arm 2 in the direction generally indicated 12. The movement is controlled by the amount of current passing through leads 7 and 8 and coil 5.

30 40 Turning now to FIG. 2 there is illustrated a single thermal actuator 20 constructed in accordance with another embodiment of the present invention. The thermal actuator 20 includes an electrical circuit comprising leads 26, 27 connecting to a serpentine resistive element 28. The resistive element 28 can comprise a copper layer in this respect, a copper stiffener 29 is provided to provide support for one end of the thermal actuator 20.

35 45 The copper resistive element 28 is constructed in a serpentine manner to provide very little tensile strength along the length of the thermal actuator 20. The copper resistive element is embedded in a polytetrafluoroethylene (PTFE) layer 32. The PTFE layer 32 has a very high coefficient of thermal expansion (approximately 770×10^{-6}). This layer undergoes rapid expansion when heated by the copper heater 28. The copper heater 28 is positioned closer to the top surface of the PTFE layer, thereby heating the upper level of the PTFE layer 32 faster than the bottom level, resulting in a bending down of the thermal actuator 20 towards the bottom of the chamber 24.

50 55 60 Turning now to FIG. 3, there is illustrated an exploded perspective view of a thermal actuator constructed in accordance with one embodiment of the present invention. The basic fabrication steps are:

- 1) Starting with the single crystal silicon wafer, which has a buried epitaxial layer 36 of silicon which is heavily doped with boron. The boron should be doped to preferably 10^{20} atoms per cm^3 of boron or more and be

approximately 3 μm thick. The lightly doped silicon epitaxial layer 35 on top of the boron doped layer should be approximately 8 μm thick, and be doped in a manner suitable for the semi-conductor device technology chosen.

- 2) On top of the silicon epitaxial layer 35 is fabricated a circuitry layer 37 according to the process chosen, up until the oxide layer over second level matter layers.
- 3) Next, a silicon nitride passivation layer 38 is deposited.
- 4) Next, the actuator 20 (FIG. 2) is constructed. The actuator comprises one copper layer 39 embedded in a PTFE layer 40. The copper layer 39 comprises both the heater portion 28 and planar portion 29 (of FIG. 2). Initially, a bottom part of the PTFE layer 40 is deposited, on top of which the copper layer 39 is then deposited. The copper layer 39 is etched to form the heater portion 28 and planar portion 29 (of FIG. 1). Subsequently, the top portion of the PTFE layer 40 is deposited to complete the PTFE layer 40 which is shown as one layer in FIG. 3 for clarity.
- 5) Etch through the PTFE, and all the way down to silicon in the region around the three sides of the thermal actuator. The etched region should be etched on all previous lithographic steps, so that the etch to silicon does not require strong selectivity against PTFE.
- 6) Etch the epitaxial silicon layer 35, which stops on (111) crystallographic planes or on heavily boron doped silicon. This etch forms the chamber 4 (FIG. 2).

Thermal actuators such as these illustrated in FIG. 1 and FIG. 2 can be utilised in many different devices in MEMS processes where actuation is required. This can include but is not limited to:

1. The utilisation of actuators in ink jet devices to actuate the ejection of ink.
2. The utilisation of actuation devices for the turbulence control of aircraft wings through the independent monitoring of turbulence and adjustment of wing surface profiles.
3. The utilisation of actuators for micro-mirror arrays devices utilised in image projection systems.
4. The utilisation of actuators in cilia arrays for the fine position adjustment of devices.
5. The utilisation of actuators in optical micro-bench positioning of optical elements.
6. The utilisation of fine optical fibre position control. Utilisation of actuators in micro-pumping.
7. The utilisation of actuators in MEMS devices such as micro-tweezers etc.

Of course, other forms of thermal actuators can just as easily be constructed in accordance with the principles of the preferred embodiment. For example a rotational actuator utilising a serpentine layer and an arcuate PTFE layer could be constructed. A push or buckle actuator could be constructed from a serpentine layer encased in a PTFE layer.

It would be appreciated by a person skilled in the art that numerous variations and/or modifications may be made to the present invention as shown in the specific embodiment without departing from the spirit or scope of the invention as broadly described. The present embodiments are, therefore, to be considered in all respects to be illustrative and not restrictive.

Ink Jet Technologies

The embodiments of the invention use an ink jet printer type device. Of course many different devices could be used. However presently popular ink jet printing technologies are unlikely to be suitable.

The most significant problem with thermal inkjet is power consumption. This is approximately 100 times that required for high speed, and stems from the energy-inefficient means of drop ejection. This involves the rapid boiling of water to produce a vapor bubble which expels the ink. Water has a very high heat capacity, and must be superheated in thermal inkjet applications. This leads to an efficiency of around 0.02%, from electricity input to drop momentum (and increased surface area) out.

The most significant problem with piezoelectric inkjet is size and cost. Piezoelectric crystals have a very small deflection at reasonable drive voltages, and therefore require a large area for each nozzle. Also, each piezoelectric actuator must be connected to its drive circuit on a separate substrate. This is not a significant problem at the current limit of around 300 nozzles per print head, but is a major impediment to the fabrication of pagewide print heads with 19,200 nozzles.

Ideally, the inkjet technologies used meet the stringent requirements of in-camera digital color printing and other high quality, high speed, low cost printing applications. To meet the requirements of digital photography, new inkjet technologies have been created. The target features include:

- low power (less than 10 Watts)
- high resolution capability (1,600 dpi or more)
- photographic quality output
- low manufacturing cost
- small size (pagewidth times minimum cross section)
- high speed (<2 seconds per page).

All of these features can be met or exceeded by the inkjet systems described below with differing levels of difficulty. 45 different inkjet technologies have been developed by the Assignee to give a wide range of choices for high volume manufacture. These technologies form part of separate applications assigned to the present Assignee as set out in the table below.

The inkjet designs shown here are suitable for a wide range of digital printing systems, from battery powered one-time use digital cameras, through to desktop and network printers, and through to commercial printing systems

For ease of manufacture using standard process equipment, the print head is designed to be a monolithic 0.5 micron CMOS chip with MEMS post processing. For color photographic applications, the print head is 100 mm long, with a width which depends upon the inkjet type. The smallest print head designed is IJ38, which is 0.35 mm wide, giving a chip area of 35 square mm. The print heads each contain 19,200 nozzles plus data and control circuitry.

Ink is supplied to the back of the print head by injection molded plastic ink channels. The molding requires 50 micron features, which can be created using a lithographically micromachined insert in a standard injection molding tool. Ink flows through holes etched through the wafer to the nozzle chambers fabricated on the front surface of the wafer.

60 The print head is connected to the camera circuitry by tape automated bonding.

Cross-Referenced Applications

The following table is a guide to cross-referenced patent applications filed concurrently herewith and discussed hereinafter with the reference being utilized in subsequent tables when referring to a particular case:

Tables of Drop-on-Demand Inkjets

Eleven important characteristics of the fundamental operation of individual inkjet nozzles have been identified. These characteristics are largely orthogonal, and so can be elucidated as an eleven dimensional matrix. Most of the eleven axes of this matrix include entries developed by the present assignee.

The following tables form the axes of an eleven dimensional table of inkjet types.

Actuator mechanism (18 types)

Basic operation mode (7 types)

Auxiliary mechanism (8 types)

15 Actuator amplification or modification method (17 types)

Actuator motion (19 types)

Nozzle refill method (4 types)

Method of restricting back-flow through inlet (10 types)

Nozzle clearing method (9 types)

Nozzle plate construction (9 types)

Drop ejection direction (5 types)

Ink type (7 types)

25 The complete eleven dimensional table represented by these rows contains 26.9 billion possible configurations of

ations are viable. It is clearly impra-

The complete eleven dimensional table represented by these axes contains 36.9 billion possible configurations of inkjet nozzle. While not all of the possible combinations result in a viable inkjet technology, many million configurations are viable. It is clearly impractical to elucidate all of the possible configurations. Instead, certain inkjet types have been investigated in detail. These are designated IJ01 to IJ45 above.

above. Other inkjet configurations can readily be derived from these 45 examples by substituting alternative configurations along one or more of the 11 axes. Most of the IJ01 to IJ45 examples can be made into inkjet print heads with characteristics superior to any currently available inkjet technology.

40 Where there are prior art examples known to the inventor, one or more of these examples are listed in the examples column of the tables below. The IJ01 to IJ45 series are also listed in the examples column. In some cases, a printer may be listed more than once in a table, where it shares characteristics with more than one entry.

Suitable applications include: Home printers, Office network printers, Short run digital printers, Commercial print systems, Fabric printers, Pocket printers, Internet WWW printers, Video printers, Medical imaging, Wide format printers, Notebook PC printers, Fax machines, Industrial printing systems, Photocopiers, Photographic minilabs etc.

The information associated with the aforementioned 11 dimensional matrix are set out in the following tables.

ACTUATOR MECHANISM (APPLIED ONLY TO SELECTED INK DROPS)		Description	Advantages	Disadvantages	Examples
Actuator Mechanism	Thermal bubble	An electrothermal heater heats the ink to above boiling point, transferring significant heat to the aqueous ink. A bubble nucleates and quickly forms, expelling the ink. The efficiency of the process is low, with typically less than 0.05% of the electrical energy being transformed into kinetic energy of the drop.	- Large force generated - Simple construction - No moving parts - Fast operation - Small chip area required for actuator	- High power - Ink carrier limited to water - Low efficiency - High temperatures required - High mechanical stress - Unusual materials required - Large drive transistors - Cavitation causes actuator failure - Kogation reduces bubble formation - Large print heads are difficult to fabricate	- Canon Bubblejet 1979 Endo et al GB patent 2,007,162 - Xerox heater-in-pit 1990 Hawkins et al USP 4,899,181 - Hewlett-Packard TIJ 1982 Vaught et al USP 4,490,728 - Kyser et al USP 3,946,398 - Zoltan USP 3,683,212 1973 Siemens USP 3,747,120 - Epson Stylus - Tektronix - II04 - Seiko Epson, Usui et al JP 25340196 - II04
Piezoelectric		A piezoelectric crystal such as lead lanthanum zirconate (PZT) is electrically activated, and either expands, shears, or bends to apply pressure to the ink, ejecting drops.	- Low power consumption - Many ink types can be used - Fast operation - High efficiency - due to actuator size	- Very large area required for actuator - Difficult to integrate with electronics - High voltage drive transistors required - Full pagewidth print heads impractical 1973 Siemens USP 3,747,120 - Requires electrical poling in high field strengths during manufacture	
Electrostrictive		An electric field is used to activate relaxor materials such as lead lanthanum zirconate titanate (PLZT) or lead magnesium niobate (PMN).	- Low power consumption - Many ink types can be used - Low thermal expansion - Electric field strength required (approx. 3.5 V/μm) - can be generated without difficulty - Does not require electrical poling	- Low maximum strain (approx. 0.01%) - Large area required for actuator due to low strain - Response speed is marginal ($\sim$10 μs) - High voltage drive transistors required - Full pagewidth print heads impractical due to actuator size	
Ferroelectric		An electric field is used to induce a phase transition between the antiferroelectric (AFE) and ferroelectric (FE) phase. Perovskite materials such as tin modified lead lanthanum zirconate titanate (PLZSnT) exhibit large strains of up to 1% associated with the AFE to FE phase transition.	- Low power consumption - Many ink types can be used - Fast operation (<1 μs) - Relatively high longitudinal strain - High efficiency - Electric field strength of around 3 V/μm can be readily provided	- Difficult to integrate with electronics - Unusual materials such as PLZSnT are required - Actuators require a large area	- II04 - II04
Electrostatic plates		Conductive plates are separated by a compressible or fluid dielectric (usually air). Upon application of a voltage, the plates attract each other and displace ink, causing drop ejection. The conductive plates may be in a comb or honeycomb	- Low power consumption - Many ink types can be used - Fast operation - need to be separated from the ink - Very large area required to achieve high forces - High voltage drive transistors may be	- Difficult to operate electrostatic devices in an aqueous environment - The electrostatic actuator will normally	II02, II04

	Description	Advantages	Disadvantages	Examples
Surface tension reduction	be pre-stressed to approx. 8 MPa. Ink under positive pressure is held in a nozzle by surface tension. The surface tension of the ink is reduced below the bubble threshold, causing the ink to egress from the nozzle.	♦ Low power consumption ♦ Simple construction ♦ No unusual materials required in fabrication ♦ High efficiency ♦ Easy extension from single nozzles to pagewidth print heads	♦ Pre-stressing may be required ♦ Requires supplementary force to effect drop separation ♦ Requires special ink surfactants ♦ Speed may be limited by surfactant properties	♦ Silverbrook, EP 0771 658 A2 and related patent applications
Viscosity reduction	The ink viscosity is locally reduced to select which drops are to be ejected. A viscosity reduction can be achieved electrothermally with most inks, but special inks can be engineered for a 100:1 viscosity reduction.	♦ Simple construction ♦ No unusual materials required in fabrication ♦ Easy extension from single nozzles to pagewidth print heads ♦ A high temperature difference	♦ Requires supplementary force to effect drop separation ♦ Requires special ink viscosity properties ♦ High speed is difficult to achieve ♦ Requires oscillating ink pressure (typically 80 degrees) is required ♦ Complex drive circuitry ♦ Complex fabrication ♦ Poor control of drop position	♦ Silverbrook, EP 0771 658 A2 and related patent applications ♦ 1993 Hadimoglu et al, EUP 550,192
Acoustic	An acoustic wave is generated and focussed upon the drop ejection region.	♦ Can operate without a nozzle plate ♦ Low efficiency	♦ Poor control of drop volume ♦ Efficient aqueous operation requires a thermal insulator on the hot side ♦ Corrosion prevention can be difficult ♦ Pigmented inks may be infeasible, as pigment particles may jam the bend actuator ♦ U41	♦ U03, U09, U17, U18 ♦ U19, U20, U21, U22 ♦ U23, U24, U27, U28 ♦ U29, U30, U31, U32 ♦ U33, U34, U35, U36 ♦ U37, U38, U39, U40
Thermoelectric bend actuator	An actuator which relies upon differential thermal expansion upon Joule heating is used.	♦ Low power consumption ♦ Many ink types can be used ♦ Simple planar fabrication ♦ Small chip area required for each actuator ♦ Fast operation ♦ High efficiency ♦ CMOS compatible voltages and currents ♦ Standard MEMS processes can be used	♦ Easy extension from single nozzles to pagewidth print heads ♦ High force can be generated ♦ PTFE is a candidate for low dielectric constant insulation in ULSI ♦ Very low power consumption ♦ Many ink types can be used ♦ Simple planar fabrication ♦ Small chip area required for each actuator ♦ Fast operation ♦ High efficiency ♦ CMOS compatible voltages and currents	♦ U09, U17, U18, U20 ♦ U21, U22, U23, U24 ♦ U27, U28, U29, U30 ♦ U31, U42, U43, U44 ♦ Requires special material (e.g. PTFE) ♦ Requires a PTFE deposition process, which is not yet standard in ULSI fabs ♦ PTFE deposition cannot be followed with high temperature (above 350° C.) processing ♦ Pigmented inks may be infeasible, as pigment particles may jam the bend actuator
High CTE thermoelectric actuator	A material with a very high coefficient of thermal expansion (CTE) such as polytetrafluoroethylene (PTFE) is used. As high CTE materials are usually non-conductive, a heater fabricated from a conductive material is incorporated. A 50 μ m long PTFE bend actuator with polysilicon heater and 15 mW power input can provide 180 μ N force and 10 μ m deflection. Actuator motions include:	♦ Easy extension from single nozzles to pagewidth print heads ♦ High force can be generated ♦ PTFE is a candidate for low dielectric constant insulation in ULSI ♦ Very low power consumption ♦ Many ink types can be used ♦ Simple planar fabrication ♦ Small chip area required for each actuator ♦ Fast operation ♦ High efficiency ♦ CMOS compatible voltages and currents	1) Bend	♦ U09, U17, U18, U20 ♦ U21, U22, U23, U24 ♦ U27, U28, U29, U30 ♦ U31, U42, U43, U44 ♦ Requires special material (e.g. PTFE) ♦ Requires a PTFE deposition process, which is not yet standard in ULSI fabs ♦ PTFE deposition cannot be followed with high temperature (above 350° C.) processing ♦ Pigmented inks may be infeasible, as pigment particles may jam the bend actuator

Description	Advantages	Disadvantages	Examples
Proximity Electrostatic pull on ink	The drops to be printed are selected by some manner (e.g. thermally induced surface tension reduction of pressurized ink). Selected drops are separated from the ink in the nozzle by contact with the print medium or a transfer roller. The drops to be printed are selected by some manner (e.g. thermally induced surface tension reduction of pressurized ink). Selected drops are separated from the ink in the nozzle by a strong electric field.	- Very simple print head fabrication can be used - The drop selection means does not need to provide the energy required to separate the drop from the nozzle - Very simple print head fabrication can be used - The drop selection means does not need to provide the energy required to separate the drop from the nozzle	- Requires close proximity between the print head and the print media or transfer roller - May require two print heads printing alternate rows of the image - Monolithic color print heads are difficult - Requires very high electrostatic field - Electrostatic field for small nozzle sizes is above air breakdown - Electrostatic field may attract dust
Magnetic pull on ink	The drops to be printed are selected by some manner (e.g. thermally induced surface tension reduction of pressurized ink). Selected drops are separated from the ink in the nozzle by a strong magnetic field acting on the magnetic ink. The actuator moves a shutter to block ink flow to the nozzle. The ink pressure is pulsed at a multiple of the drop ejection frequency.	- Very simple print head fabrication can be used - The drop selection means does not need to provide the energy required to separate the drop from the nozzle - Very simple print head fabrication can be used - The drop selection means does not need to provide the energy required to separate the drop from the nozzle	- Requires magnetic ink - Ink colors other than black are difficult - Requires very high magnetic fields
Shutter			- Requires ink pressure modulator - Friction and wear must be considered - Stiction is possible
Shuttered grill			- Requires ink pressure modulator - Friction and wear must be considered - Stiction is possible
Pulsed magnetic pull on ink pusher			- Requires an external pulsed magnetic field - Requires special materials for both the actuator and the ink pusher - Complex construction
AUXILIARY MECHANISM (APPLIED TO ALL NOZZLES) Auxiliary Mechanism			- Drop ejection energy must be supplied by individual nozzle actuator - Monolithic color print heads are difficult - Electrostatic field for small nozzle sizes is above air breakdown - Electrostatic field may attract dust
None			- Drop ejection energy must be supplied by individual nozzle actuator - Monolithic color print heads are difficult - Electrostatic field for small nozzle sizes is above air breakdown - Electrostatic field may attract dust

Description	Advantages	Disadvantages	Examples
Oscillating ink pressure (including acoustic stimulation)	The ink pressure oscillates, providing much of the drop ejection energy. The actuator selects which drops are to be fired by selectively blocking or enabling nozzles. The ink pressure oscillation may be achieved by vibrating the print head, or preferably by an actuator in the ink supply. The print head is placed in close proximity to the print medium. Selected drops protrude from the print head further than unselected drops, and contact the print medium. The drop soaks into the separation. Drops are printed to a transfer roller instead of straight to the print medium. A transfer roller can also be used for proximity drop separation.	◆ Oscillating ink pressure can provide a refill pulse, allowing higher operating speed ◆ The actuators may operate with much lower energy ◆ Acoustic lenses can be used to focus the sound on the nozzles ◆ Low power ◆ High accuracy ◆ Simple print head construction	the#thermal bubble ◆ I01-I07, I09, I11 ◆ I12, I14, I20, I22 ◆ I23-I45 ◆ Silverbrook, EP 0771 658 A2 and related patent applications ◆ I08, I13, I15, I17 ◆ I18, I19, I21
Media proximity	The print head is placed in close proximity to the print medium. Selected drops protrude from the print head further than unselected drops, and contact the print medium. The drop soaks into the separation.	◆ Precision assembly required ◆ Ink pressure phase and amplitude must be carefully controlled ◆ Acoustic reflections in the ink chamber must be designed for ◆ Paper fibers may cause problems ◆ Cannot print on rough substrates	◆ Silverbrook, EP 0771 658 A2 and related patent applications
Transfer roller	An electric field is used to accelerate selected drops towards the print medium.	◆ Bulky ◆ Expensive ◆ Complex construction ◆ Tektronix hot melt piezoelectric inkjet	◆ Silverbrook, EP 0771 658 A2 and related patent applications ◆ Any of the II series ◆ Tone-Jet
Electrostatic	An electric field is used to accelerate selected drops towards the print medium.	◆ High accuracy ◆ Wide range of print substrates can be used ◆ Ink can be dried on the transfer roller ◆ Low power ◆ Simple print head construction	◆ Field strength required for separation of small drops is near or above air breakdown ◆ Requires strong magnetic field ◆ Requires strong magnetic field ◆ Does not require magnetic materials to be integrated in the print head ◆ Very low power operation is possible ◆ Small print head size
Direct magnetic field	A magnetic field is used to accelerate selected drops of magnetic ink towards the print medium.	◆ Low power ◆ Simple print head construction ◆ Does not require magnetic materials to be integrated in the print head ◆ Current densities may be high, resulting in electromigration problems	◆ Silverbrook, EP 0771 658 A2 and related patent applications ◆ I06, I16 ◆ I10
Cross magnetic field	The print head is placed in a constant magnetic field. The Lorentz force in a current carrying wire is used to move the actuator.	◆ Magnetic field is used to cyclically attract a paddle, which pushes on the ink. A small actuator moves a catch, which selectively prevents the paddle from moving.	◆ Complex print head construction ◆ Magnetic materials required in print head
Pulsed magnetic field	A pulsed magnetic field is used to directly drive the drop ejection process.	◆ Operational simplicity ◆ insufficient travel, or insufficient force, to efficiently drive the drop ejection process	◆ Many actuator mechanisms have ◆ I01, I02, I06, I07 ◆ I16, I25, I26 ◆ Thermal Bubble
ACTUATOR AMPLIFICATION OR MODIFICATION METHOD			
Actuator amplification			
None	No actuator mechanical amplification is used. The actuator directly drives the drop ejection process.		

-continued

	Description	Advantages	Disadvantages	Examples
Differential expansion bend actuator	An actuator material expands more on one side than on the other. The expansion may be thermal, piezoelectric, magnetostriuctive, or other mechanism.	◆ Provides greater travel in a reduced print head area ◆ The bend actuator converts a high force low travel actuator mechanism to high travel, lower force mechanism. ◆ Very good temperature stability ◆ High speed, as a new drop can be fired before heat dissipates ◆ Cancels residual stress of formation ◆ Increased travel ◆ Reduced drive voltage due to pinholes	◆ High stresses are involved ◆ Care must be taken that the materials do not delaminate ◆ Residual bend resulting from high temperature or high stress during formation ◆ High stresses are involved ◆ Care must be taken that the materials do not delaminate	◆ Piezoelectric ◆ II03, II09, II17-II24 ◆ II27, II29-II39, II42, II43, II44 ◆ II40, II41 ◆ Some piezoelectric ink jets
Transient bend actuator	A trilayer bend actuator where the two outside layers are identical. This cancels bend due to ambient temperature and residual stress. The actuator only responds to transient heating of one side or the other.			
Actuator stack	A series of thin actuators are stacked. This can be appropriate where actuators require high electric field strength, such as electrostatic and piezoelectric actuators.	◆ Increases the force available from an actuator ◆ Multiple actuators can be positioned to control ink flow accurately	◆ Actuator forces may not add linearly, reducing efficiency	◆ II12, II13, II18, II20 ◆ II22, II28, II32, II43 ◆ II15 ◆ Requires print head area for the spring
Multiple actuators	Multiple smaller actuators are used simultaneously to move the ink. Each actuator need provide only a portion of the force required.			
Linear Spring	A linear spring is used to transform a motion with small travel and high force into a longer travel, lower force motion.	◆ Matches low travel actuator with higher travel requirements ◆ Non-contact method of motion transformation ◆ Better coupling to the ink ◆ High stress in the spring		
Reverse spring	The actuator loads a spring. When the actuator is turned off, the spring releases. This can reverse the force/distance curve of the actuator to make it compatible with the force/time requirements of the drop ejection.			
Coiled actuator	A bend actuator is coiled to provide greater travel in a reduced chip area.			◆ II17, II21, II34, II35
Flexure bend actuator	A bend actuator has a small region near the fixtue point, which flexes much more readily than the remainder of the actuator. The actuator flexing is effectively converted from an even coiling to an angular bend, resulting in greater travel of the actuator tip.			◆ Generally restricted to planar implementations due to extreme fabrication difficulty in other orientations. ◆ Care must be taken not to exceed the elastic limit in the flexure area
Gears	Gears can be used to increase travel at the expense of duration. Circular	◆ Low force, low travel actuators can be used ◆ Moving parts are required ◆ Several actuator cycles are required		◆ II13

-continued

	Description	Advantages	Disadvantages	Examples
Catch	gears, rack and pinion, ratchets, and other gearing methods can be used. The actuator controls a small catch. The catch either enables or disables movement of an ink pusher that is controlled in a bulk manner.	- Can be fabricated using standard surface MEMS processes - Very low actuator energy - Very small actuator size	- More complex drive electronics - Complex construction - Friction, friction, and wear are possible - Complex construction - Requires external force - Unsuitable for pigmented inks	♦ II10
Buckle plate	A buckle plate can be used to change a slow actuator into a fast motion. It can also convert a high force, low travel actuator into a high travel, medium force motion.	Very fast movement achievable	- Must stay within elastic limits of the materials for long device life - High stresses involved - Generally high power requirement	♦ S. Hirata et al, "An Ink-jet Head...," Proc. IEEE MEMS, Feb. 1996, pp 418-422
Tapered magnetic pole Lever	A tapered magnetic pole can increase travel at the expense of force. A lever and fulcrum is used to transform a motion with small travel and high force into a motion with longer travel and lower force. The lever can also reverse the direction of travel.	- Linearizes the magnetic force/distance curve - Matches low travel actuator with higher travel requirements - Fulcrum area has no linear movement, and can be used for a fluid seal - High mechanical advantage	- Complex construction - High stress around the fulcrum	♦ II14
Rotary impeller	The actuator is connected to a rotary impeller. A small angular deflection of the actuator results in a rotation of the impeller vanes, which push the ink against stationary vanes and out of the nozzle. A refractive or diffractive (e.g. zone plate) acoustic lens is used to concentrate sound waves.	No moving parts	- Complex construction - Unsuitable for pigmented inks	♦ II28
Acoustic lens	A sharp point is used to concentrate an electrostatic field.	Simple construction	- Large area required - Only relevant for acoustic ink jets	♦ 1993 Hadimoglu et al, EUP 550,192
Sharp conductive point			- Difficult to fabricate using standard VLSI processes for a surface ejection - Only relevant for electrostatic ink jets	♦ 1993 Erlod et al, EUP 572,220
ACTUATOR MOTION				
Actuator motion				♦ High energy is typically required to achieve volume expansion. This leads to thermal stress, cavitation, and koggation in thermal inkjet implementations
Volume expansion	The volume of the actuator changes, pushing the ink in all directions.		High fabrication complexity may be required to achieve perpendicular motion	♦ Hewlett-Packard Thermal Inkjet
Linear, normal to chip surface	The actuator moves in a direction normal to the print head surface. The nozzle is typically in the line of movement.	Efficient coupling to ink drops ejected normal to the surface		♦ II01, II02, II04, II07
Linear, parallel to chip surface	The actuator moves parallel to the print head surface. Drop ejection may still be normal to the surface.	Suitable for planar fabrication	- Friction - Stiction	♦ II12, II13, II15, II33, II34, II35, II36

-continued

	Description	Advantages	Disadvantages	Examples
Membrane push	An actuator with a high force but small area is used to push a stiff membrane that is in contact with the ink.	The effective area of the actuator becomes the membrane area	- Fabrication complexity - Actuator size - Difficulty of integration in a VLSI process	1982 Howkins USP 4,459,601
Rotary	The actuator causes the rotation of some element, such a grill or impeller	- Rotary levers may be used to increase travel - Small chip area requirements	- Device complexity - May have friction at a pivot point	II05, II08, II13, II28
Bend	The actuator bends when energized. This may be due to differential thermal expansion, piezoelectric expansion, magnetostriction, or other form of relative dimensional change.	A very small change in dimensions can be converted to a large motion.	Requires the actuator to be made from at least two distinct layers, or to have a thermal difference across the actuator	1970 Kyser et al USP 3,946,398 1973 Steimme USP 3,747,120 - II03, II09, II10, II19 - II23, II24, II25, II29 - II30, II31, II33, II34 - II35 - II06
Swivel	The actuator swivels around a central pivot. This motion is suitable where there are opposite forces applied to opposite sides of the paddle, e.g., Lorenz force.	- Allows operation where the net linear force on the paddle is zero - Small chip area requirements	Inefficient coupling to the ink motion	II26, II32
Straighten	The actuator is normally bent, and straightens when energized.	Can be used with shape memory alloys where the austenitic phase is planar	Requires careful balance of stresses to ensure that the quiescent bend is accurate	II36, II37, II38
Double bend	The actuator bends in one direction when one element is energized, and bends the other way when another element is energized.	- One actuator can be used to power two nozzles. - Reduced chip size. - Not sensitive to ambient temperature	- Difficult to make the drops ejected by both bend directions identical. - A small efficiency loss compared to equivalent single bend actuators.	1985 Fishbeck USP 4,584,590
Shear	Energizing the actuator causes a shear motion in the actuator material.	Can increase the effective travel of piezoelectric actuators	Not readily applicable to other actuator mechanisms	1985 Fishbeck USP 4,584,590
Radial constriction	The actuator squeezes an ink reservoir, forcing ink from a constricted nozzle.	Relatively easy to fabricate single nozzles from glass tubing as macroscopic structures	- High force required - Inefficient	1970 Zoltan USP 3,683,212
Coil/uncoil	A coiled actuator uncoils or coils more tightly. The motion of the free end of the actuator ejects the ink.	- Easy to fabricate as a planar VLSI process - Small area required, therefore low cost - Can increase the speed of travel	- Difficult to fabricate for non-planar devices - Poor out-of-plane stiffness	II17, II21, II24, II35
Bow	The actuator bows (or buckles) in the middle when energized.	- Maximum travel is constrained - High force required	- Mechanically rigid - The structure is pinned at both ends, so has a high out-of-plane rigidity - Good fluid flow to the region behind the actuator increases efficiency	- II16, II18, II27 - II18
Push-Pull	Two actuators control a shutter. One actuator pulls the shutter, and the other pushes it.	Not readily suitable for inkjets which directly push the ink	Design complexity	II20, II42
Curl inwards	A set of actuators curl inwards to reduce the volume of ink that they enclose.	Relatively large chip area	Relatively simple	II43
Curl outwards	A set of actuators curl outwards,			

-continued

Description	Advantages	Disadvantages	Examples
pressurizing ink in a chamber surrounding the actuators, and expelling ink from a nozzle in the chamber			
Iris	Multiple vanes enclose a volume of ink. These simultaneously rotate, reducing the volume between the vanes. The actuator vibrates at a high frequency.	◆ High efficiency ◆ Small chip area ◆ The actuator can be physically distant from the ink	◆ High fabrication complexity ◆ Not suitable for pigmented inks ◆ Large area required for efficient operation at useful frequencies ◆ Acoustic coupling and crosstalk ◆ Complex drive circuitry ◆ Poor control of drop volume and position ◆ Various other tradeoffs are required to eliminate moving parts
Acoustic vibration			◆ 1993 Hadimioglu et al, EUP 550,192 ◆ 1993 Elrod et al, EUP 572,220
None	In various ink jet designs the actuator does not move.	◆ No moving parts	◆ Silverbrook, EP 0771 658 A2 and related patent applications ◆ Tone-jet
NOZZLE REFILL METHOD			
Nozzle refill method			
Surface tension	After the actuator is energized, it typically returns rapidly to its normal position. This rapid return sucks in air through the nozzle opening. The ink surface tension at the nozzle then exerts a small force restoring the meniscus to a minimum area.	◆ Fabrication simplicity ◆ Operational simplicity	◆ Low speed ◆ Surface tension force relatively small compared to actuator force ◆ Long refill time usually dominates the total repetition rate
Shuttered oscillating ink pressure	Ink to the nozzle chamber is provided at a pressure that oscillates at twice the drop ejection frequency. When a drop is to be ejected, the shutter is opened for 3 half cycles: drop ejection, actuator return, and refill.	◆ High speed ◆ Low actuator energy, as the actuator need only open or close the shutter, instead of ejecting the ink drop	◆ Requires common ink pressure oscillator ◆ May not be suitable for pigmented inks
Refill actuator	After the main actuator has ejected a drop a second (refill) actuator is energized. The refill actuator pushes ink into the nozzle chamber. The refill actuator returns slowly, to prevent its return from emptying the chamber again.	◆ High speed, as the nozzle is actively refilled	◆ Requires two independent actuators per nozzle ◆ II09
Positive ink pressure	The ink is held a slight positive pressure. After the ink drop is ejected, the nozzle chamber fills quickly as surface tension and ink pressure both operate to refill the nozzle.	◆ High refill rate, therefore a high drop repetition rate is possible	◆ Silverbrook, EP 0771 658 A2 and related patent applications ◆ Highly hydrophobic print head surfaces are required ◆ Alternative for: ◆ II01-II07, II10-II14 ◆ II16, II20, II22-II45
METHOD OF RESTRICTING BACK-FLOW THROUGH INLET			

-continued

Description	Advantages	Disadvantages	Examples
Inlet back-flow restriction method			
Long inlet channel	- Design simplicity - Operational simplicity - Reduces crosstalk	- Restricts refill rate - May result in a relatively large chip area - Only partially effective	- Thermal inkjet - Piezoelectric inkjet
Positive ink pressure	- Drop selection and separation forces can be reduced - Fast refill time	Requires a method (such as a nozzle rim or effective hydrophobizing, or both) to prevent flooding of the ejection surface of the print head.	- Silverbrook, EP 0771 658 A2 and related patent applications ◆ Possible operation of the following: ◆ I01-I07, I09-I12 ◆ I14, I16, I20, I22, I23-I34, I36-I41 ◆ I44
Baffle	- The refill rate is not as restricted as the long inlet method. - Reduces crosstalk	- Design complexity - May increase fabrication complexity (e.g. Tektronix hot melt Piezoelectric print heads).	- HP Thermal Ink Jet ◆ Tektronix piezoelectric ink jet
Flexible flap restricts inlet		Significantly reduces back-flow for edge-shooter thermal ink jet devices	Canon
Inlet filter		- Additional advantage of ink filtration - Ink filter may be fabricated with no additional process steps	- Increased fabrication complexity - Inelastic deformation of polymer flap results in creep over extended use - Restricts refill rate - May result in complex construction
Small inlet compared to nozzle	Design simplicity	- Restricts refill rate - May result in a relatively large chip area - Only partially effective	- I02, I37, I44 - I09
Inlet shutter		Increases speed of the ink-jet print head operation	- Requires careful design to minimize the negative pressure behind the paddle ◆ I01, I03, I05, I06 ◆ I07, I10, I11, I14 ◆ I16, I22, I23, I25 ◆ I28, I31, I32, I33 ◆ I34, I35, I36, I39
The inlet is located behind the ink-pushing surface		Back-flow problem is eliminated	- Requires careful design to minimize the negative pressure behind the paddle ◆ I01, I03, I05, I06 ◆ I07, I10, I11, I14 ◆ I16, I22, I23, I25 ◆ I28, I31, I32, I33 ◆ I34, I35, I36, I39

-continued

Description	Advantages	Disadvantages	Examples
Part of the actuator moves to shut off the inlet. Nozzle actuator does not result in ink back-flow	◆ Significant reductions in back-flow can be achieved ◆ Compact designs possible ◆ Ink back-flow problem is eliminated	◆ Small increase in fabrication complexity ◆ None related to ink back-flow on actuation	◆ II40, II41 ◆ II07, II20, II26, II31 ◆ Silverbrook, EP 0771 ◆ 658 A2 and related patent applications ◆ Valve-jet ◆ Tone-jet ◆ II08,II13,II15,II17 ◆ II18,II19,II21
NOZZLE CLEARING METHOD Nozzle Cleaning method	All of the nozzles are fired periodically, before the ink has a chance to dry. When not in use the nozzles are sealed (capped) against air. The nozzle firing is usually performed during a special clearing cycle, after first moving the print head to a cleaning station. In systems which heat the ink, but do not boil it under normal situations, nozzle clearing can be achieved by over-powering the heater and boiling ink at the nozzle. The actuator is fired in rapid succession. In some configurations, this may cause heat build-up at the nozzle which boils the ink, clearing the nozzle. In other situations, it may cause sufficient vibrations to dislodge clogged nozzles. Where an actuator is not normally driven to the limit of its motion, nozzle clearing may be assisted by providing an enhanced drive signal to the actuator.	◆ No added complexity on the print head	◆ May not be sufficient to displace dried ink ◆ Requires higher drive voltage for clearing ◆ May require larger drive transistors ◆ Effectiveness depends substantially upon the configuration of the inkjet nozzle ◆ Not suitable where there is a hard limit to actuator movement
Normal nozzle firing	All of the nozzles are fired periodically, before the ink has a chance to dry. When not in use the nozzles are sealed (capped) against air. The nozzle firing is usually performed during a special clearing cycle, after first moving the print head to a cleaning station. In systems which heat the ink, but do not boil it under normal situations, nozzle clearing can be achieved by over-powering the heater and boiling ink at the nozzle. The actuator is fired in rapid succession. In some configurations, this may cause heat build-up at the nozzle which boils the ink, clearing the nozzle. In other situations, it may cause sufficient vibrations to dislodge clogged nozzles. Where an actuator is not normally driven to the limit of its motion, nozzle clearing may be assisted by providing an enhanced drive signal to the actuator.	◆ Most ink jet systems ◆ II01-II07, II09-II12 ◆ II14, II16, II20, II22 ◆ II23-II34, II36-II45	◆ Most ink jet systems ◆ II01-II07, II09-II11 ◆ II14, II16, II20, II22 ◆ II23-II25, II36-II45 ◆ II36-II45 ◆ May be used with: ◆ II03, II09, II16, II20 ◆ II23, II24, II25, II27 ◆ II29, II30, II31, II32 ◆ II39, II40, II41, II42 ◆ II43, II44, II45 ◆ II08, II13, II15, II17 ◆ II18, II19, II21
Rapid succession of actuator pulses	An ultrasonic wave is applied to the ink chamber. This wave is of an appropriate amplitude and frequency to cause sufficient force at the nozzle to clear blockages. This is easiest to achieve if the ultrasonic wave is at a		◆ High implementation cost if system does not already include an acoustic actuator
Extra power to ink pushing actuator	◆ A simple solution where applicable		
Acoustic resonance			

-continued

Description	Advantages	Disadvantages	Examples
Nozzle clearing plate	resonant frequency of the ink cavity. A microfabricated plate is pushed against the nozzles. The plate has a post for every nozzle. The array of posts	◆ Can clear severely clogged nozzles ◆ Accurate mechanical alignment is required ◆ Moving parts are required ◆ There is risk of damage to the nozzles ◆ Accurate fabrication is required ◆ Requires pressure pump or other pressure actuator ◆ Expensive ◆ Wasteful of ink	◆ Silverbrook, EP 0771 658 A2 and related patent applications ◆ May be used with all IJ series ink jets
Ink pressure pulse	The pressure of the ink is temporarily increased so that ink streams from all of the nozzles. This may be used in conjunction with actuator energizing. A flexible 'blade' is wiped across the print head surface. The blade is usually fabricated from a flexible polymer, e.g. rubber or synthetic elastomer.	◆ May be effective where other methods cannot be used ◆ Effective for planar print head surfaces ◆ Low cost ◆ Difficult to use if print head surface is non-planar or very fragile ◆ Requires mechanical parts ◆ Blade can wear out in high volume print systems ◆ Fabrication complexity	◆ Many ink jet systems ◆ Many IJ series ink jets
Print head wiper	A separate heater is provided at the nozzle although the normal drop ejection mechanism does not require it. The heaters do not require individual drive circuits, as many nozzles can be cleared simultaneously, and no imaging is required.	◆ Can be effective where other nozzle clearing methods cannot be used ◆ Can be implemented at no additional cost in some inkjet configurations	◆ Can be used with many IJ series ink jets
Separate ink boiling heater			◆ High temperatures and pressures are required to bond nozzle plate ◆ Minimum thickness constraints ◆ Differential thermal expansion ◆ Each hole must be individually formed ◆ Special equipment required ◆ Slow where there are many thousands of nozzles per print head ◆ May produce thin burrs at exit holes
NOZZLE PLATE CONSTRUCTION			◆ 1993 Watansabe et al., USP 5,208,604 ◆ K. Bean, IEEE Transactions on Electron Devices, Vol. ED-25, No. 10, 1978 pp 1185-1195 ◆ Xerox 1990 Hawkin et al., USP 4,899,181 ◆ 1970 Zoltan USP 3,683,212
Nozzle plate construction			◆ Two part construction ◆ High cost ◆ Requires precision alignment ◆ Nozzles may be clogged by adhesive
Electroformed nickel	A nozzle plate is separately fabricated from electroformed nickel, and bonded to the print head chip.	◆ Fabrication simplicity	◆ Hewlett Packard Thermal Inkjet
Laser ablated or drilled polymer	Individual nozzle holes are ablated by an intense UV laser in a nozzle plate, which is typically a polymer such as polyimide or polysulphone	◆ No masks required ◆ Can be quite fast ◆ Some control over nozzle profile is possible ◆ Equipment required is relatively low cost	◆ Canon Bubblejet ◆ 1988 Serel et al., SPIE, Vol. 998 Excimer Beam Applications, pp. 76-83
Silicon micro-machined	A separate nozzle plate is micromachined from single crystal silicon, and bonded to the print head wafer.	◆ High accuracy is attainable	◆ 1993 Watansabe et al., USP 5,208,604 ◆ K. Bean, IEEE Transactions on Electron Devices, Vol. ED-25, No. 10, 1978 pp 1185-1195 ◆ Xerox 1990 Hawkin et al., USP 4,899,181 ◆ 1970 Zoltan USP 3,683,212
Glass capillaries	Fine glass capillaries are drawn from glass tubing. This method has been used for making individual nozzles, but is difficult to use for bulk	◆ No expensive equipment required ◆ Simple to make single nozzles ◆ Very small nozzle sizes are difficult to form ◆ Not suited for mass production	

-continued

Description	Advantages	Disadvantages	Examples
surface micro-machined using VLSI lithographic processes	- Manufacturing of print heads with thousands of nozzles. - layer using standard VLSI deposition techniques. Nozzles are etched in the nozzle plate using VLSI lithography and etching.	- Monolithic - Low cost - Existing processes can be used	- nozzle plate to form the nozzle chamber - Surface may be fragile to the touch 658 A2 and related patent applications - II01, II02, II04, II11 - II12, II17, II18, II20 - II22, II24, II27, II28 - II29, II30, II31, II32 - II33, II34, II36, II37 - II38, II39, II40, II41 - II42, II43, II44 - II03, II05, II06, II07 - II08, II09, II10, II13 - II14, II15, II16, II19 - II21, II23, II25, II26
Monolithic, etched through substrate	The nozzle plate is a buried etch stop in the wafer. Nozzle chambers are etched in the front of the wafer, and the wafer is thinned from the back side. Nozzles are then etched in the etch stop layer.	- High accuracy (<1 μm) - Monolithic - Low cost - No differential expansion	- Requires long etch times - Requires a support wafer Ricoh 1995 Sekiya et al USP 5,412,413 1993 Hadimoglu et al EUP 550,192 1993 Elrod et al EUP 572,220 1989 Saito et al USP 4,799,068 - Difficult to control drop position accurately - Crosstalk problems
No nozzle plate	Various methods have been tried to eliminate the nozzles entirely, to prevent nozzle clogging. These include thermal bubble mechanisms and acoustic lens mechanisms	No nozzles to become clogged	- Drop firing detection is sensitive to wicking. 1993 Elrod et al EUP 572,220 - Difficult to control drop position accurately - Crosstalk problems
Trough	- Each drop ejection has a trough through which a paddle moves. - There is no nozzle plate.	- Reduced manufacturing complexity - Monolithic - No nozzles to become clogged	- Drop firing detection is sensitive to wicking. 1989 Saito et al USP 4,799,068 - Difficult to control drop position accurately - Crosstalk problems
Nozzle slit instead of individual nozzles	The elimination of nozzle holes and replacement by a slit encompassing many actuator positions reduces nozzle clogging, but increases crosstalk due to ink surface waves		
DROP EJECTION DIRECTION			
Ejection direction			
Edge (edge shooter)	Ink flow is along the surface of the chip, and ink drops are ejected from the chip edge.	- Simple construction - No silicon etching required - Good heat sinking via substrate - Mechanically strong - Ease of chip handling	- Nozzles limited to edge - High resolution is difficult - Fast color printing requires one print head per color Canon Bubblejet 1979 Endo et al GB patent 2,007,162 Xerox heat-in-pit 1990 Hawkins et al USP 4,899,181 Tone-jet 1982 Vaught et al USP 4,490,728 II02, II11, II12, II20 II22
Surface ('roof shooter')	Ink flow is along the surface of the chip, and ink drops are ejected from the chip surface, normal to the plane of the chip.	- No bulk silicon etching required - Silicon can make an effective heat sink - High ink flow - Mechanical strength - Suitable for page-width print - High nozzle packing	Maximum ink flow is severely restricted Silverbrook, EP 0771 658 A2 and related patent applications
Through chip, forward ('up shooter')			

-continued

INKTYPE	Description	Advantages	Disadvantages	Examples
Ink type				
Through chip, reverse (down shooter)	Ink flow is through the chip, and ink drops are ejected from the rear surface of the chip. density therefore low	♦ High ink flow ♦ Suitable for pagewidth print heads ♦ High nozzle packing	♦ Requires wafer thinning ♦ Requires special handling during manufacture	♦ II04, II17, II18, II24 ♦ II27-II45 ♦ II01, II03, II05, II07, II08, II09, II10 ♦ II13, II14, II15, II16
Through actuator	Ink flow is through the actuator, which is not fabricated as part of the same substrate as the drive transistors.	manufacturing cost ♦ Suitable for piezoelectric print heads	♦ Pagewidth print heads require several thousand connections to drive circuits ♦ Cannot be manufactured in standard CMOS fabs ♦ Complex assembly required	♦ II19, II21, II23, II25 ♦ II26 ♦ Epson Stylus ♦ Tektronix hot melt piezoelectric ink jets
Methyl Ethyl Ketone (MEK)	Water based ink which typically contains: water, dye, surfactant, humectant, and biocide. Modem ink dyes have high waterfastness, light fastness	♦ Environmentally friendly ♦ No odor	♦ Slow drying ♦ Corrosive ♦ Bleeds on paper	♦ Most existing inkjets ♦ All II series ink jets ♦ Silverbrook EP 0771 658 A2 and related patent applications ♦ II02, II04, II21, II26 ♦ II27, II30 ♦ Silverbrook, EP 0771 658 A2 and related patent applications ♦ Piezoelectric ink-jets (with significant restrictions)
Aqueous, pigment	Water based ink which typically contains: water, pigment, surfactant, humectant, and biocide. Pigments have an advantage in reduced bleed, wicking and strikethrough.	♦ Environmentally friendly ♦ No odor ♦ Reduced bleed ♦ Reduced wicking ♦ Reduced strikethrough	♦ Slow drying ♦ Corrosive ♦ Pigment may clog nozzles ♦ Pigment may clog actuator mechanisms ♦ Cookies paper	♦ All II series inkjets
Alcohol (ethanol, 2-butanol, and others)	MEK is a highly volatile solvent used for industrial printing on difficult surfaces such as aluminum cans.	♦ Very fast drying ♦ Prints on various substrates such as metals and plastics	♦ Odorous	♦ All II series ink jet
Phase change (hot melt)	Alcohol based inks can be used where the printer must operate at temperatures below the freezing point of water. An example of this is in-camera consumer photographic printing.	♦ Fast drying ♦ Operates at sub-freezing temperatures ♦ Reduced paper cockle ♦ Low cost	♦ Slight odor ♦ Flammable	♦ Tektronix hot melt piezoelectric inks ♦ Printed pages may 'block' 1989 Nowak USP 4,820,346 ♦ All II series inkjets
Oil	Alcohol based inks are extensively used in offset printing. They have	♦ No drying time-ink instantly freezes on the print medium ♦ Almost any print medium can be used ♦ No paper cockle occurs ♦ No wicking occurs ♦ No bleed occurs ♦ High solubility medium for some dyes	♦ High viscosity ♦ Printed ink typically has a 'waxy' feel ♦ Printed pages may 'block' ♦ Ink temperature may be above the curie point of permanent magnets ♦ Ink heaters consume power ♦ Long warm-up time ♦ High viscosity: this is a significant limitation for use in inkjets, which	. All II series ink jets

-continued

Description	Advantages	Disadvantages	Examples
advantages in improved characteristics on paper (especially no wicking or cockle). Oil soluble dyes and pigments are required. A microemulsion is a stable, self forming emulsion of oil, water, and surfactant. The characteristic drop size is less than 100 nm, and is determined by the preferred curvature of the surfactant.	◆ Does not cockle paper ◆ Does not wick through paper ◆ Stops ink bleed ◆ High dye solubility ◆ Water, oil, and amphiphilic soluble dyes can be used ◆ Can stabilize pigment suspensions	◆ Usually require a low viscosity. Some short chain and multi-branched oils have a sufficiently low viscosity. ◆ Slow drying ◆ Viscosity higher than water ◆ Cost is slightly higher than water based ink ◆ High surfactant concentration required (around 5%)	◆ All IJ series ink jets

Ink Jet Printing

A large number of new forms of ink jet printers have been developed to facilitate alternative ink jet technologies for the image processing and data distribution system. Various combinations of ink jet devices can be included in printer devices incorporated as part of the present invention. Australian Provisional Patent Applications relating to these ink jets which are specifically incorporated by cross reference include:

Australian Provisional Number	Filing Date	Title
PO8066	Jul. 15, 1997	Image Creation Method and Apparatus (IJ01)

45 Ink Jet Manufacturing

Further, the present application may utilize advanced semiconductor fabrication techniques in the construction of 50 large arrays of ink jet printers. Suitable manufacturing techniques are described in the following Australian provisional patent specifications incorporated here by cross-reference:

Australian Provisional Number	Filing Date	Title
PO7935	15-Jul-97	A Method of Manufacture of an Image Creation Apparatus (IJM01)
PO7936	15-Jul-97	A Method of Manufacture of an Image Creation Apparatus (IJM02)
PO7937	15-Jul-97	A Method of Manufacture of an Image Creation Apparatus (IJM03)
PO8061	15-Jul-97	A Method of Manufacture of an Image Creation Apparatus (IJM04)
PO8054	15-Jul-97	A Method of Manufacture of an Image Creation Apparatus (IJM05)
PO8065	15-Jul-97	A Method of Manufacture of an Image Creation Apparatus (IJM06)
PO8055	15-Jul-97	A Method of Manufacture of an Image Creation Apparatus (IJM07)
PO8053	15-Jul-97	A Method of Manufacture of an Image Creation Apparatus (IJM08)
PO8078	15-Jul-97	A Method of Manufacture of an Image Creation Apparatus (IJM09)
PO7933	15-Jul-97	A Method of Manufacture of an Image Creation Apparatus (IJM10)
PO7950	15-Jul-97	A Method of Manufacture of an Image Creation Apparatus (IJM11)
PO7949	15-Jul-97	A Method of Manufacture of an Image Creation Apparatus (IJM12)
PO8060	15-Jul-97	A Method of Manufacture of an Image Creation Apparatus (IJM13)
PO8059	15-Jul-97	A Method of Manufacture of an Image Creation Apparatus (IJM14)
PO8073	15-Jul-97	A Method of Manufacture of an Image Creation Apparatus (IJM15)
PO8076	15-Jul-97	A Method of Manufacture of an Image Creation Apparatus (IJM16)
PO8075	15-Jul-97	A Method of Manufacture of an Image Creation Apparatus (IJM17)
PO8079	15-Jul-97	A Method of Manufacture of an Image Creation Apparatus (IJM18)
PO8050	15-Jul-97	A Method of Manufacture of an Image Creation Apparatus (IJM19)
PO8052	15-Jul-97	A Method of Manufacture of an Image Creation Apparatus (IJM20)
PO7948	15-Jul-97	A Method of Manufacture of an Image Creation Apparatus (IJM21)
PO7951	15-Jul-97	A Method of Manufacture of an Image Creation Apparatus (IJM22)
PO8074	15-Jul-97	A Method of Manufacture of an Image Creation Apparatus (IJM23)
PO7941	15-Jul-97	A Method of Manufacture of an Image Creation Apparatus (IJM24)
PO8077	15-Jul-97	A Method of Manufacture of an Image Creation Apparatus (IJM25)
PO8058	15-Jul-97	A Method of Manufacture of an Image Creation Apparatus (IJM26)

PP3989	9-Jun-98	A Method of Manufacture of an Image Creation Apparatus (IJM40)
PP3990	9-Jun-98	A Method of Manufacture of an Image Creation Apparatus (IJM42)
PP3986	9-Jun-98	A Method of Manufacture of an Image Creation Apparatus (IJM43)
PP3984	9-Jun-98	A Method of Manufacture of an Image Creation Apparatus (IJM44)
PP3982	9-Jun-98	A Method of Manufacture of an Image Creation Apparatus (IJM45)

Fluid Supply

Further, the present application may utilize an ink delivery system to the ink jet head. Delivery systems relating to the supply of ink to a series of ink jet nozzles are described in the following Australian provisional patent specifications, the disclosure of which are hereby incorporated by cross-reference:

Australian Provisional Number	Filing Date	Title
PO8003	Jul. 15, 1997	Supply Method and Apparatus (F1)
PO8005	Jul. 15, 1997	Supply Method and Apparatus (F2)
PO9404	Sep. 23, 1997	A Device and Method (F3)

MEMS Technology

Further, the present application may utilize advanced semiconductor microelectromechanical techniques in the construction of large arrays of ink jet printers. Suitable microelectromechanical techniques are described in the following Australian provisional patent specifications incorporated here by cross-reference:

45

Australian Provisional Number	Filing Date	Title
PO7943	Jul. 15, 1997	A device (MEMS01)
PO8006	Jul. 15, 1997	A device (MEMS02)
PO8007	Jul. 15, 1997	A device (MEMS03)
PO8008	Jul. 15, 1997	A device (MEMS04)
PO8010	Jul. 15, 1997	A device (MEMS05)
PO8011	Jul. 15, 1997	A device (MEMS06)
50 PO7947	Jul. 15, 1997	A device (MEMS07)
PO7945	Jul. 15, 1997	A device (MEMS08)
PO7944	Jul. 15, 1997	A device (MEMS09)
PO7946	Jul. 15, 1997	A device (MEMS10)
PO9393	Sep. 23, 1997	A Device and Method (MEMS11)
55 PP0875	Dec. 12, 1997	A Device (MEMS12)
PP0894	Dec. 12, 1997	A Device and Method (MEMS13)
60		

IR Technologies

Further, the present application may include the utilization of a disposable camera system such as those described in the following Australian provisional patent specifications incorporated here by cross-reference:

-continued

Australian Provisional Number	Filing Date	Title
PP0895	Dec. 12, 1997	An Image Creation Method and Apparatus (IR01)
PP0870	Dec. 12, 1997	A Device and Method (IR02)
PP0869	Dec. 12, 1997	A Device and Method (IR04)
PP0887	Dec. 12, 1997	Image Creation Method and Apparatus (IR05)
PP0885	Dec. 12, 1997	An Image Production System (IR06)
PP0884	Dec. 12, 1997	Image Creation Method and Apparatus (IR10)
PP0886	Dec. 12, 1997	Image Creation Method and Apparatus (IR12)
PP0871	Dec. 12, 1997	A Device and Method (IR13)
PP0876	Dec. 12, 1997	An Image Processing Method and Apparatus (IR14)
PP0877	Dec. 12, 1997	A Device and Method (IR16)
PP0878	Dec. 12, 1997	A Device and Method (IR17)
PP0879	Dec. 12, 1997	A Device and Method (IR18)
PP0883	Dec. 12, 1997	A Device and Method (IR19)
PP0880	Dec. 12, 1997	A Device and Method (IR20)
PP0881	Dec. 12, 1997	A Device and Method (IR21)

DotCard Technologies

Further, the present application may include the utilization of a data distribution system such as that described in the following Australian provisional patent specifications incorporated here by cross-reference:

Australian Provisional Number	Filing Date	Title
PP2370	Mar. 16, 1998	Data Processing Method and Apparatus (Dot01)
PP2371	Mar. 16, 1998	Data Processing Method and Apparatus (Dot02)

Artcam Technologies

Further, the present application may include the utilization of camera and data processing techniques such as an Artcam type device as described in the following Australian provisional patent specifications incorporated here by cross-reference:

Austral-ian Provis-ional Filing Number	Date	Title
PO7991	15-Jul-97	Image Processing Method and Apparatus (ART01)

50 We claim:

1. A micromechanical thermal actuator having a bend axis arranged to curve upon actuation, said actuator comprising: a first material having a first coefficient of thermal expansion; a serpentine heater element having a relatively lower coefficient of thermal expansion in thermal contact with said first material and adapted to heat said first material on demand; said serpentine heater element having a majority of its length perpendicular to the bend axis of the actuator enabling the heater element to be elongated upon heating so as to accommodate the expansion of said first material.
2. An actuator as claimed in claim 1 wherein said serpentine heater element comprises a layer of poly-silicon.

45

3. An actuator as claimed in either claim 1 or claim 2 wherein said first material is provided in a first layer and the actuator further comprises a second layer having a relatively higher coefficient at thermal expansion than said first layer, the heater element being in thermal contact with said first layer and said second layer such that on heating said heater element, said actuator moves from a first quiescent position to a second actuation position.
4. An actuator as claimed in claim 3 wherein said heater element is sandwiched between said first layer and said second layer.

10

46

5. An actuator as claimed in either claim 1 or claim 2 wherein the first material forms a layer and the heater element is embedded in the first material toward one surface of the layer.
6. An actuator as claimed in claim 1 wherein said first material comprises polytetrafluoroethylene.
7. An actuator as claimed in claim 3 wherein said second layer is selected from the group comprising silicon dioxide and silicon nitride.
